Primary Examiner — Rosemary K Tarcza*Assistant Examiner* — Seth David Kumpf(74) *Attorney, Agent, or Firm* — Chun-Ming Shih;
Lanway IPR Services(57) **CLAIM**The ornamental design for a socket for extension cord, as
shown and described.

DESCRIPTION

FIG. 1 is a top front right side perspective view of a socket
for extension cord, showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The socket for extension cord is shown with a symbolic
break in its length. The appearance of any portion of the
article between the break lines forms no part of the claimed
design.The broken lines depict portions of the socket for extension
cord that form no part of the claimed design.**1 Claim, 7 Drawing Sheets**(56)
